UNITED STATES PATENT OFFICE.

FRANKLIN G. TALLERDAY, OF TRYON CITY, NORTH CAROLINA, AS
SIGNOR OF ONE-FOURTH TO GEORGE C. TALLERDAY, OF POPLAR
GROVE, ILLINOIS.

PAWL-AND-RATCHET MECHANISM.

SPECIFICATION forming part of Letters Patent No. 439,613, dated October 28, 1890.

Application filed May 31, 1890. Serial No. 353,851. (No model.)

To all whom it may concern:

Be it known that I, FRANKLIN G. TALLERDAY, a citizen of the United States, residing at Tryon City, Polk county, and State of North Carolina, have invented certain new and useful Improvements in Pawl-and-Ratchet Mechanisms, of which the following is a specification.

The object of my invention is the modification and improvement of the mechanism shown and described in an application for a patent for an improvement in pawl-and-ratchet mechanisms now pending in the United States Patent Office, filed May 10, 1889, and having the Serial Number 310,339, so as to adapt the same to be used in connection with suitable auxiliary devices as a windmill regulator; and the invention consists of certain new and useful features of construction and combinations of parts hereinafter described, and pointed out in the claims.

Referring to the accompanying drawings, which form a part of this specification, Figure 1 is a side elevation of the pawl-and-ratchet mechanism provided with my improvement, the driving-arm being broken away to show the construction and connection of the parts located behind the same. Fig. 2 is a like view of the same, except that the ratchet-wheel thereof is turned a half-revolution from the position shown in Fig. 1. Fig. 3 is an under side view of the more intricate parts of the machine in operative position and relation. Fig. 4 is a back side view of the pallet and middle portion of the driving-arm and their respective connections. Fig. 5 is a view of my improvement mounted on a windmill-tower and operatively connected with a windmill, (not shown,) a pump, and a water-tank.

Like letters of reference indicate corresponding parts throughout the several views.

A is the base-plate of the machine.

B is a ratchet-wheel having a portion of its teeth, as those included between the letters B', depressed below the remainder thereof, and being provided with a peripheral depression B² at the outer termination of the more prominent teeth—those included between the

letters B³. As about one-third of the periphery of the ratchet-wheel is idle, it is neither desirable nor necessary that that portion be provided with teeth. The wheel B is mounted on the horizontal bearing B⁴, which is rigidly connected with the base-plate A.

C is a longitudinally-reciprocating detent adapted to engage endwise with the teeth B⁵ B⁶ of the ratchet-wheel B and prevent the same from revolving in one direction, and mounted in slideways D D', which are covered with caps D² D³.

C' is a stud projecting from the outside of the detent C.

C² is a detent-actuating spring coiled about the detent C and included between the end 65 of the slideway and cap D D² and stud C'.

E is a longitudinally - reciprocating bar mounted in the slideways D D' and serving intermediately to connect the detent C with a pallet, to be described hereinafter.

E' is a cross-piece integral or rigidly connected with the bar E and curved in the form of a segment of a circle, to serve as a guide for a part to be described hereinafter.

E² is a stud projecting transversely and 75 horizontally from the outside of the bar E.

F is a lever engaging with the stud E² for simultaneously disengaging the detent C and pallet, to be described, from the ratchet-wheel B, if desired, and is mounted on the 80 pivot F'.

G is a bearing-plate, from which project the pallet-bearings G' G².

G³ is a longitudinally-laterally-reciprocating pallet adapted to engage with the teeth 85 B⁵ B⁶ of the ratchet-wheel B and revolve the same in a direction opposite to that prevented by the detent C.

G⁴ is a stud projecting from the outside of the pallet G³.

G⁵ is a pallet-actuating spring coiled about the pallet G³ and included between the bearing G' and stud G⁴.

H is a driving-arm, whereto the bearing-plate G is firmly secured, pivotally connected 95 with the bearing B⁴ and the pumping-rod I through the media of the horizontal slot H' therein and the pin I'.

J is an ungearing-arm, secured by one end thereof to the ratchet-wheel B.

K is an ungearing-wire, one end whereof is connected with the arm J by means of the 5 holes J' therein.

L is a bell-crank mounted in the ordinary way on the tower A'.

L' is a wire connecting the upper end of the bell-crank L with the lower end of the 10 lever F by means of a hole F' therein.

L³ is a wire depending from the hole L⁴ in the bell-crank L. L⁵ is a float of wood or other suitable material attached to the lower end of the wire L³ and supported by water M 15 in the tank M'.

N is a pump in connection, through the pumping-rod I, with the arm II.

Fig. 1 shows the machine with the parts in 20 the positions they assume when the same is at rest, the tank filled, and the windmill (not shown) out of gear.

Considering the machine, as shown in Fig. 1, as the starting-point, its operation is as follows: Whenever any considerable amount of 25 water is withdrawn from the tank M' by the drinking of animals or otherwise, the float L⁵ descends, and through the media of the wire L³, bell-crank L, wire L', lever F, reciprocating bar E, and cross-piece E' forces back 30 and disengages the detent C and pallet G³ from the ratchet-wheel B and retains them in the position indicated by dotted lines in Figs. 1 and 3, whereupon a weight, (not shown,) held in suspension by the wire K while taut, descends and throws the windmill into gear and at the same time draws the wire K upward, thereby carrying the arm J and revolving the ratchet-wheel B to the 35 position shown in Fig. 2. The mill having 40 swung into the wind and being now in gear commences and continues to revolve and drive the pumping-rod I until the tank M' is filled, when the float L⁵ is lifted by the water in the tank, thereby releasing the lever F and allowing the detent C and pallet G³ to re- 45 engage with the ratchet-wheel B, as shown in Fig. 2. The mill, will continue to revolve longitudinally reciprocating the pumping-rod I, which reciprocates the driving-arm II, as indicated by the double arrows and dotted lines, 50 and with it the pallet G³, which engages with the teeth of the ratchet-wheel B and revolves it, together with the arm J, to the position shown in Fig. 1, thereby, through the wire K, 55 throwing the mill out of gear and leaving the machine and its connections in precisely the same positions as at the outset. As the pallet G³ descends with each stroke of the driving-arm II, the detent C prevents the 60 ratchet-wheel B from being revolved downward by the action of the pallet and weight (not shown) operating upon the arm J through the medium of the wire K. Obviously the detent C does not prevent the pallet G³ from 65 revolving the ratchet-wheel B and the arm J upward or in a direction opposite of that just mentioned. The wire K remains slack while

the mill is pumping, the ratchet-wheel B being in the position shown in Fig. 2, and the detent C and pallet G³ being held out of engagement therewith, as indicated by the dotted lines X X' in Figs. 1 and 3, until the float L⁵ rises, and through the intermediate connections forces the lever F to release the detent C and pallet G³, when the springs C² G⁵ 70 will cause their points to re-engage with the teeth B⁵ of the ratchet-wheel B, as shown in Fig. 2. The effect of the first few strokes of the driving-arm II, detent C, and pallet G³, after the two latter come into engagement 75 with the depressed teeth B⁵ in Fig. 2, is simply to take up the slack of the wire K, preparatory to throwing the mill out of gear. During the operation of taking up the slack 80 of the wire K, to which reference has just been made, the ratchet-wheel B oscillates on its bearing sufficiently to cause the points of the detent C and the pallet G³ and the teeth of the ratchet-wheel B, when the teeth thereof 85 are all of the same length, to grind against each 90 other and wear away the points of the detent, pallet, and teeth.

I have found by trial that if the teeth employed in the preliminary operation of taking up the slack of the wire K, as those included between the letters B' are depressed 95 so that the points of the detent C and pallet G³ only partially engage with the same, the wearing away of those parts is practically obviated. By the time the slack is taken out 100 of the wire K the detent C and the pallet G³ will be well engaged with the more prominent teeth B⁶ of the ratchet-wheel B. A few strokes of the driving-arm II will then, 105 through the media of the arm J and wire K, lift the weight (not shown) and throw the mill completely out of gear. However, after the detent C and the pallet G³ have passed into the depression B², the pumping-rod I may make two or three partial strokes and 110 cause the detent C and pallet G³ to move up and down, which they may freely do, traveling back and forth in the depression B², which is of such depth that their points do not come 115 in contact with the bottom thereof, and thereby suffer wear from contact therewith.

By constructing the ratchet-wheel B with the depressed teeth B⁵ and a peripheral depression B², as shown and described, I have perfectly adapted the mechanism to be used 120 in regulating windmills.

I claim—

1. In combination, a ratchet-wheel having a portion of its teeth depressed below the remainder thereof and being provided with a 125 peripheral depression at the outer termination of the more prominent teeth, the detent adapted to engage with and stop the same, the pallet arranged to engage with and revolve said ratchet-wheel, the bar connecting 130 the detent and pallet, the lever for operating said bar and connections, and the necessary bearings for supporting and operating all of said parts, substantially as set forth.

2. In combination, a ratchet-wheel having a portion of its teeth depressed below the remainder thereof, a detent adapted to engage with and prevent the same from revolving in one direction, a pallet arranged to engage with said ratchet-wheel and revolve the same in a direction opposite to that prevented by said detent, a vertically-reciprocating driving-arm whereon the said pallet is mounted and whereby it is operated, a bar connecting said detent and pallet, and means for operating said bar and connections, substantially as described, and for the purpose specified.
3. In combination, in a pawl-and-ratchet mechanism, a ratchet-wheel having a portion of its teeth, as those included between the letters B', depressed below the remainder thereof and being provided with a peripheral depression B² at the outer termination of the more prominent teeth, those included be-

tween the letters B³, a longitudinally-reciprocating detent adapted to engage with and prevent the same from revolving in one direction, a longitudinally-vertically-reciprocating pallet arranged to engage with and revolve said ratchet-wheel in a direction opposite to that prevented by said detent, a vertically-reciprocating arm whereon said pallet is mounted and whereby it is operated, a longitudinally-reciprocating bar connecting said detent and pallet, a lever for operating said bar and the parts connected therewith, a suitable base-plate, and proper bearings for uniting and supporting all of said parts in operative position and relation, substantially as specified, and for the purpose set forth.

FRANKLIN G. TALLERDAY.
